UNITED STATES PATENT OFFICE.

BENJAMIN F. LOLLIS, OF BERWYN, ILLINOIS, ASSIGNOR TO THE RAILROAD SUPPLY COMPANY, OF CHICAGO, ILLINOIS, A CORPORATION OF ILLINOIS.

SHIPPING MEANS.

Application filed January 23, 1925. Serial No. 4,159.

The present invention relates to shipping means.

The present invention will be described in connection with certain signaling mechanism which is useful for railway signaling purposes.

Railway signaling mechanism involves the use of certain electrical relays which operate upon relatively low voltage and which, therefore, require rather careful adjustment.

Such adjustment is commonly made in shops equipped for the purpose, the workmen who install said relays on the railroad lines being required only to connect said relays in circuit.

An object of the present invention is to provide a construction whereby electrical relay devices may, after having been carefully adjusted, be shipped to their destination and installed with a maximum of convenience.

A further object is to provide means for conveniently holding movable parts of electrical relay mechanism when said devices are in shipment, which holding means may be retained as a permanent part of said mechanism and which may be used repeatedly to perform its holding functions if subsequent shipments of said relay mechanism should be found to be necessary.

Further objects will appear as the description proceeds.

Referring to the drawings—

Figure 1 is a view in front elevation of a relay device, such as is used in railway signaling mechanism;

Figure 2 is a sectional view taken along the plane indicated by the arrows 2—2 of Figure 1;

Figure 3 represents a detail of construction;

Figure 4 is a view similar to that of Figure 2 but showing a slight modification; and

Figures 5 and 6 represent details of the modification shown in Figure 4.

The numeral 1 indicates a housing, which is provided with a cover 2. The housing 1 provides sight openings which may be closed by means of transparent closures indicated by the numerals 3—3.

The cover 2 provides supporting means for a pair of electromagnets 4—4, which electromagnets comprise cores 5—5 and solenoids 6—6. Cooperatively associated with the lower ends of the cores 6—6 is the arma-

ture 7, which may be pivotally supported by the bracket 8 and which may have its attracted position defined and limited by the adjustable abutment 7'. The armature 7 provides mounting means for a plurality of resilient contact fingers 9—9, four of which are shown in the illustrated embodiment of the present invention. Said fingers 9—9 are adapted to contact with relatively fixed contact members 10—10, which are adjustably supported from the cover 2. The contacts 10—10 may be connected in the electrical circuit to be controlled.

As noted above, electrical relay devices as commonly used require a relatively fine adjustment and should be quite accurate in their performance. For this reason, great care should be taken in the mounting of the armature 7 and the resilient contacts 9—9 carried thereby. It is not ordinarily practicable to entrust this fine adjustment to the workmen in the field, for which reason such adjustment is performed in shops equipped for the purpose, the relays being shipped with their moving parts securely held against vibration. Said relays are commonly sealed to prevent access to the interior thereof by workmen who are installing same in service or by other unauthorized persons. It has been common practice heretofore to hold the relay armature of an electrical signaling device in proximity to the cooperating core faces, when said device is being shipped, by means of a screw which extends into the interior of the housing and which is manipulable from the exterior of said housing. Said screw ordinarily extends through the bottom of the housing and projects upwardly, contacting with the underside of the armature of the relay device.

The housing 1 in ordinary practice is provided with relatively short legs 11—11 adapted to support said housing upon a flat surface. When the expedient referred to is employed, such holding screw will be turned down to permit free action of the armature. It has not been good practice to entirely remove said screw for the reason that the removal thereof would leave an opening in the housing 1 through which dirt could enter.

It has been the practice heretofore to merely turn down the holding screw whereby to free the armature of the relay mechanism, after which the outer end of said holding screw has been cut off, whereby said holding

screw would not interfere with the proper functioning of the legs 11-11. This practice is open to the objection that when it is necessary to again ship the relay device for inspection and possible readjustment, said holding screw, having had its lower end cut off, is useless for again holding the relay armature in its home position.

According to the present invention, an improved holding means is provided involving a member which may be held either in operative position for armature holding functions, or held in a position entirely free of said armature. In neither of said positions will said screw interfere with the functioning of the legs 11-11.

Referring now to the armature holding means shown in Figures 1, 2 and 3, the base of the housing 1 is provided with an upward standing boss 12, which boss may have secured thereto the bushing 13, which provides holding means for a nut 14 located adjacent to the top of said boss 12. Said nut 14 receives the screw-threaded pin 15, the upper end of which may contact with the underside of the armature 7. The lower end of said screw-threaded pin 15 may be provided with a slot 16 for the reception of a screw driver.

The numeral 17 indicates a locking member of special configuration. Said locking member 17 has a screw-threaded portion 18 adapted to receive the screw-threaded pin 15 and an elongated shell portion 19, which at its lower end is provided with a head portion 20 which may be conveniently gripped with a pair of pliers. The sleeve portion 19 of the locking member 17 may have an internal diameter greater than the diameter of the screw-threaded pin 15, whereby a screw driver may readily be inserted within said sleeve portion 19 for the purpose of turning the screw-threaded pin 15. The screw-threaded pin 15 should be of such a length that in its armature freeing position the lower end of said screw will lie above the plane marking the lower extremities of the legs 11-11, whereby said screw when in its retracted or armature freeing position will not interfere with the functioning of said legs 11-11. The nut 14 will be positioned to hold the screw 15 throughout its range of movement and will be displaced inwardly of housing 1 a sufficient distance from the lower end of screw 15 (when said screw 15 is in armature holding position) to permit the engagement of the lower portion of member 15 by the screw-threaded portion 18 of the locking member 17.

The mode of operation of the above described embodiment of the present invention will be clear without detailed explanation. It will be sufficient to state that after the armature 7 has been adjusted in the

shop, the screw 15 will be turned up in the nut 14 to an extent necessary to hold said armature 7 in its attracted position, whereby vibration of said armature during shipment is prevented. When said screw 15 is in the position referred to, the locking member 17 may be turned up on the lower end of screw 15 into contact with the nut 14, whereby said screw 15 will be securely locked against turning movement.

The lower portion of the head 20 of the locking member 17 will at all times lie above the plane marking the lower extremities of the legs 11-11. When the relay device has reached its destination and is to be in service, a workman need only loosen the locking member 17 by rotating the same, after which said workman may turn down the screw 15 to a position in which it will not interfere with the proper operation of armature 7. By reason of the fact that the nut 14 lies at a level considerably higher than the plane marking the bases of the legs 11-11, said screw 15 is allowed a considerable range of movement before the lower end of said screw reaches the plane marking the bases of said legs 11-11.

When the screw 15 has been turned down a sufficient distance the locking member 17 may again be rotated to lock the screw 15 in its retracted position. By reason of the present invention, the screw 15 may be retained in the nut 14 at all times, whereby ingress of foreign matter into the relay mechanism is prevented. Moreover, said screw 15 will be securely locked at all times, and even when in its retracted position will not project below the plane marking the bases of legs 11-11, so that the screw will not interfere at any time with the proper functioning of said legs.

When it is found necessary to again ship the relay mechanism, said screw 15 may readily be turned up to its armature holding position after communicating a slight turning movement to the locking member 17 to release same. It will be clear, therefore, that the present invention provides a construction in which the screw 15 will perform the functions of holding the armature 7 in immovable condition during shipment, will form a closure for the housing 1 at all times, and will obviate the necessity for any mutilation of said screw when said screw is in non-holding position.

Referring now to the modification illustrated in Figures 4 to 6, the boss 12 within the housing 1 is provided with the bushing or nut 21, said bushing or nut being molded or otherwise secured within said boss 12. Said bushing 21 is preferably provided with the screw-threaded hole 22 at its upper extremity, which screw-threaded hole receives the holding pin 23.

Said pin 23 is screw-threaded at its upper

extremity as indicated by the numeral 24, which screw-threaded portion is adapted to have engagement with the screw-threaded hole 25 located near the swinging edge of the armature 7 and is also adapted to have engagement with the nut or bushing 21 to prevent ingress of dirt. The pin 23 has a head 26 at its lower extremity, which head has the slot 27 for receiving a screw driver or similar tool. Between the screw-threaded portion 24 and the head 26, the pin 23 has a reduced shank which can slide through the screw-threaded hole 22. The lower extremity of the bushing 21 is internally screw-threaded as indicated by the numeral 28, which screw-threaded portion is adapted to have engagement with the screw-threaded portion 29 of the bushing 30. Said bushing 30 at its lower extremity is provided with the knurled head 31. At its upper extremity said bushing 30 is split longitudinally to provide prongs 32-32. Said bushing 30, therefore, comprises a split sleeve. The bushing 21 is tapered internally near its upper extremity, as indicated by the numeral 33, which tapered portion is adapted to receive the prongs 32-32 of the split bushing 30.

The embodiment of the present invention illustrated in Figures 4, 5 and 6 has the advantage that the armature 7 and its associated contact members can be held in any desired position within the range of movement of said armature 7 and said members. This advantage is important, for the reason that many railroads specify that in shipment the relay armature shall be positively held out of engaging position at both ends of the range of movement of said armature. According to the structure shown in Figures 4 to 7, the screw-threaded portion 24 may be readily screwed into the armature 7, the reduced shank portion of the pin 23 permitting the free rotation of said pin relative to the bushing 21. At this time, of course, the bushing 30 will be turned back a sufficient distance from the tapered portion 33 of the bushing 21 to permit such free rotation of the pin 23. After the pin 24 has been secured to the armature 7, said armature may be held, by means of a screw driver or other implement, in its preferred position in the range of movement of said armature, after which the knurled head 31 of the bushing 30 may be turned up to a position wherein the prongs 32-32 have wedging engagement between the tapered portion 33 of the bushing 21 and the shank of the pin 23, whereby said pin 23 and consequently the armature 7 will be held securely against movement relative to the remainder of the relay mechanism. The pin 23 will be of such a length that when in its uppermost position it will hold the armature 7 in close proximity to the stops 7'-7'. Due to

the elongated bushing 21, the pin 23 may be lowered to the lowest position required without having the lower end of said pin project below the base line 11-11 of the instrument. The shank of the pin 23 between the head 26 and the screw-threaded portion 24 thereof will be of substantially uniform diameter, whereby only a very slight movement of sleeve 30 is required to free the pin 23 for axial movement or to grip said pin.

Though a preferred embodiment of the present invention has been described in detail, it will be clear that many modifications will occur to those skilled in the art. It is intended to cover all such modifications that fall within the scope of the appended claims.

What is claimed is:

1. In relay mechanism, in combination, a movable member, a housing for said member, means for securely holding said member in immovable position for shipping purposes, said means including a pin adapted to be immovably supported by said housing, said pin and housing being provided with a holding member for locking said pin in adjusted positions axially of said pin, said holding member having its holding portion placed midway of the range of travel of said pin, said pin being of such a length that when said pin is in a position to hold said movable member in an immovable position the opposite end of said pin will be adjacent to said holding portion and when said pin is in a position to free said movable member said opposite end will lie within the boundaries of said housing and the other end of said pin will be adjacent to said holding portion, said holding member being provided with a portion projecting to a position at which same may be conveniently manipulated.

2. In a relay device, in combination, a housing, said housing having supporting legs adapted to rest upon a flat surface, a movable member within said housing, a boss within said housing, which boss provides communication from the exterior of said housing to the interior thereof, a pin mounted within said boss and adapted to engage said movable member to hold said movable member immovable, said pin being of such length that when retracted to permit free movement of said movable member it will lie within the plane bounded by the bases of said legs, and a holding member for locking said pin, said holding member including an elongated sleeve portion extending into said housing and permitting access to the end of said pin.

3. In a relay mechanism, in combination, a movable member, a housing for said movable member, and means for holding immovable said movable member for shipping

purposes, said means including a screw-threaded pin for engaging said movable member, a nut for holding said screw-threaded pin, a boss carried by said housing interiorly thereof, said nut being located at the inner extremity of said boss, and a screw-threaded sleeve member for locking said pin, said sleeve member being of a length to extend from said pin to the exterior of said housing.

4. In a relay mechanism, in combination, a movable member, a housing for said movable member and means for holding immovable said movable member for shipping purposes, said means including a pin having screw-threaded engagement with said movable member, a boss carried by said housing interiorly thereof, and a sleeve member in said boss having a portion for engaging said pin, said sleeve portion being of a length to extend from said pin to the exterior of said housing member, the pin engaging portion of said sleeve member being located midway of the range of travel of said pin.

5. In a relay mechanism, in combination, a movable member, a housing for said movable member and means for holding immovable said movable member for shipping purposes, said means including a pin having screw-threaded engagement with said movable member, a boss carried by said housing interiorly thereof, and a sleeve member in said boss having a portion for engaging said pin, said sleeve portion being of a length to extend from said pin to the exterior of said housing member, the pin engaging portion of said sleeve member being located midway of the range of travel of said pin, said boss being provided with a nut for holding

said screw-threaded pin in a predetermined position.

6. In relay mechanism, in combination, a movable member, a housing for said member, and means for securely holding said member in immovable position for shipping purposes, said means including a pin adapted to be immovably supported by said housing, said pin and housing being provided with a holding member for locking said pin in adjusted positions axially of said pin, said holding member having its holding portion placed midway of the range of travel of said pin.

7. In a relay device, in combination, a housing, said housing having supporting legs adapted to rest upon a flat surface, a movable member within said housing, a pin mounted within said boss and adapted to engage said movable member to hold said movable member immovable, said pin being of such length that when retracted to permit free movement of said movable member it will lie within the plane bounded by the bases of said legs, and a holding member for locking said pin, said holding member including an elongated sleeve portion extending into said boss and permitting access to the end of said pin.

8. In a relay mechanism, in combination, a movable member, a housing for said movable member, a pin for holding said movable member in a predetermined position, and a holding member for said pin having screw-threaded engagement with said housing and adapted to have locking engagement with said housing and said pin.

Signed at Chicago, Illinois, this 19th day of January, 1925.

BENJAMIN F. LOLLISS.
